METAL SHEAR

Lorenz Iversen, Pittsburgh, Pa., assignor to Mesta Machine Company, Pittsburgh, Pa., a corporation of Pennsylvania

Application December 22, 1944, Serial No. 569,358

6 Claims. (Cl. 164—56)

This invention relates to metal shears and, in particular, to a plate shear adapted for cutting large and heavy metal plates.

Plate shears heretofore in use have been subject to many disadvantages, particularly when they are of such size as to cut very large, thick plates. My improved shear is a self-contained hydraulically operated shear, which constitutes a compact unit of superior design and construction, and having great flexibility of operation.

In the accompanying drawings illustrating a present preferred embodiment of the invention,

Figure 1 is a front elevation of the shear of my invention;

Figure 2 is a plan view;

Figure 3 is a partial vertical section taken along the plane of line III—III of Figure 2;

Figure 4 is an end elevation such as would be seen by looking from the right in Figure 1;

Figure 5 is a transverse section taken along the plane of line V—V of Figures 1 and 2;

Figure 6 is a view partly in front elevation, with certain parts removed, and partly in section along the plane of line VI—VI of Figure 2;

Figure 7 is a partial vertical section taken along the plane of line VII—VII of Figure 2;

Figure 8 is a plan view with parts omitted and a part broken away showing the pump cylinders and the ram cooperating therewith in section on a horizontal plane through their axes;

Figure 9 is a partial elevation of the control valves such as would be seen by looking from the left in Figures 1 and 8; and

Figure 10 is a partial section taken along the plane of line X—X of Figure 9.

General arrangement

Referring in detail to the drawings, and for the present to Figures 1 through 7, there is shown a base 10 carrying uprights 11 and 12. A table 13 including a main casting 13a supporting a stationary shear blade 14 is also mounted on the base between the uprights. A plate 13b on the casting 13a forms the working surface of the table. A plate-manipulating roller 15 is journaled longitudinally of the table 13 in bearings carried on posts 16 slidable vertically in the casting 13a. The plate 13b has a slot through which the roller 15 partially projects when the posts 16 are raised. The roller 15 is driven by a gear-motor 17 through shafts 18, 19 and 20, the latter including universal joints 21. The shafts are connected by bevel gears 22 and 23.

For the purpose of raising the roller 15 to operative position for manipulating a plate,

there is a fluid-pressure cylinder 24 connected by a link 25 to a crank 26 on a rock shaft 27. The rock shaft is mounted in bearings 28 secured to the casting 13a by bolts 29. Lifting fingers 30 on the shaft 27 engage the lower ends of the posts 16 to raise them when fluid under pressure is admitted to the cylinder 24. The roller 15 may be lowered by releasing the fluid pressure from the cylinder 24.

Just behind the shear blade 14 there is a conveyor for carrying away the sheared scrap. It consists of a conveyor chain 31 moving on a track 32 secured to the back of the casting 13a and around driving and idler sprockets 33 and 34. The sprocket 33 is driven by any convenient means through a shaft 35.

Upper shear knife mounting

As best shown in Figures 4 and 5, the uprights 11 and 12 are massive ribbed castings having portions 36 overhanging the table 13 and conveyor 31, and providing recesses 37 to give ample room for manipulation, as well as to accommodate the portion of the plate which is to be sheared off. Pockets 38 are formed in the upper part of the overhanging portions 36. Guides 39 below the pockets accommodate the ends of a vertically slidable crosshead 40 which carries the movable shear blade. The ends of the crosshead 30 are confined in the guides by keeper plates 41 secured to the uprights by T-head bolts 42. A movable shear blade 43 is mounted on the crosshead at an angle to the fixed blade 14 so that the shearing operation is a progressive one.

Each of the pockets 38 accommodates a fluid motor of the positive-displacement type for actuating the crosshead 40 and the shear blade 43. These motors consist of a ram-and-cylinder combination, one end of which is secured to one 40 of the uprights 11 and 12, and the other end of which is operatively connected to the corresponding end of the crosshead 40. The fixed elements of the ram-and-cylinder combinations in this embodiment of the invention, are rams 45 depending from blocks 44, secured on top of the portions 36 of the uprights by eye bolts 45. Anchor pins 46 extend through holes in the uprights and through the eyes of the bolts 45. The blocks 44 have rams 47 formed integral therewith which fit into cylinders 48 lying within the pockets 38. The lower ends of the cylinders engage pivotal bearing blocks 49 carried on the ends of the crosshead 40. Fluid-supply passages 50 and 51 drilled in the blocks 44 and rams 47 permit fluid under pressure to be supplied to the

interior of the cylinders as explained hereinafter, thereby forcing the cylinders and the crosshead downwardly.

The crosshead 40 is biased toward its uppermost position by spring suspensions 52 mounted near the ends of a girder 53 extending between the uprights and secured thereto by bolts 54. The top position of the crosshead is fixed by the engagement of pads 55 on the crosshead with pads 56 on the bottom of the girder.

One of the spring suspensions 52 is shown in Figure 3. Two of these suspensions are secured to each end of the crosshead as indicated in Figures 2 and 8. Each suspension comprises nested compression springs 57 supporting a hanger rod 58 secured to a lifting lug 59 formed on the crosshead. The springs 57 are compressed as the crosshead is lowered by the supply of fluid under pressure to the interior of the cylinders 48. As soon as the pressure on the fluid is relieved, the springs raise the crosshead to its uppermost position, thereby expelling fluid from the cylinders.

Plate clamping mechanism

A beam 60 extends between the uprights and is secured to the keeper plates 41 by screws 61. (Pockets 62 are formed in the beam to accommodate the lugs 59 when the crosshead descends.) A set of fluid-pressure cylinders 63 is spaced along the beam 60. The cylinders have pistons therein provided with plungers 64 adapted, when extended, to engage a plate on the table and clamp it firmly in position for shearing. Oil under pressure is delivered to the cylinders 63 by a pump 65 driven by a motor 66, both of which are mounted on the girder 53. A valve 67, also mounted on the girder, controls the flow of oil through suitable pipe connections, as shown in Figures 1 and 2, to a manifold passage 68 in the beam 60. Connecting passages through the beam (not shown) extend from the passage 68 to the cylinders 63 through individual valves 69. The valves 69 are provided so that the rate of movement of the several plungers may be equalized or otherwise regulated. The cylinders 63 have compression springs therein (not shown) below the plungers for returning the latter to raised position when the pressure on the fluid in the cylinders is relieved.

Pump mechanism for actuating shear blade

The cylinders 48 are supplied with oil under pressure from a pump 70 through control valves formed in a valve block 71. The pump comprises a cylinder 72 slidable on horizontal guides in one end of a gear case 73 which extends between the uprights 11 and 12. A fixed ram 74, integral with the block 71, extends into the cylinder 72. The block and the ram are secured to the case by bolts 75.

The cylinder 72 has two coaxial chambers in tandem, the relative diameters of which are such that the same amount of oil is displaced from each chamber by a given movement of the cylinder. The ram 74, as shown, has portions corresponding in size to the diameters of the two chambers in the cylinder. Passages 76 and 77 extending through the ram communicate with the chambers, respectively.

The pump cylinder has trunnions 73 for connecting rods 79. The other ends of the rods engage eccentrics 80 secured to a shaft 81 journaled in the case 73. The shaft 81 is driven by a motor 82 mounted on the girder 53. The motor is coupled to a shaft 83 journaled in the gear case, hav-

ing a pinion 84 thereon meshing with a gear 85 on the shaft 81. Flywheels 86 are mounted on the shaft 83 to increase the inertia of the rotating system.

As the gear 85 is driven, the cylinder 72 is first forced toward the ram 74 and oil in the cylinder chambers is forced outwardly through the passages 76 and 77, after which the cylinder is returned to the position in which it is shown in Figure 8. In use, the motor is continuously operated.

Poppet valves 87 and 88 are provided for controlling the passage of oil to the rams 47 (see Figures 9 and 10). These valves are normally urged against seats formed in chambers 89 and 90 by compression springs 91, the valves being slidable in sleeves 92. The springs and sleeves are held in position by plugs 93 bolted to the block 71. The passages 76 and 77 in the ram 74 intersect the chambers 89 and 90, as best shown in Figure 9.

Connecting passages 94 and 95 extend downwardly from the chambers 89 and 90 to a horizontal channel 96. A pipe connection 97 extends from one end of this channel to an oil reservoir 98 formed in the upper removable portion or cover of the gear case 73. A rock shaft 99 is journaled in bearings 100 in the channel 96 and has lifting fingers 100 thereon for engaging the lower ends of the stems of the valves 87 and 88. By this construction, the valves 87 and 88 may be raised from their seats by counter-clockwise rotation of the shaft 99 as viewed in Figure 10.

So long as the valves 87 and 88 are lifted from their seats, oil is free to flow from the cylinder 72, as it moves leftward, to the reservoir 98 through the passages 76 and 77, the valve chambers 89 and 90, passages 94 and 95, channel 96 and pipe 97. When the cylinder is retracted, the oil flows back into the chambers thereof from the reservoir by the same paths. This cycle is repeated during continuous operation of the motor 82 until the valves 87 and 88 are closed.

If the valves 87 and 88 are closed, oil supplied from the chambers in the pump cylinder through passages 76 and 77 to the valve chambers 89 and 90 can pass only through passages 101 and 102 in the block 71, from which pipe connections 103 and 104 extend to the piston blocks 44 on the uprights 11 and 12, respectively. The crosshead 40 is thus forced downwardly compressing the springs of suspensions 52, when the pump is operated with the valves 87 and 88 closed. Since equal amounts of oil are displaced from the two chambers of the cylinder 72, both ends of the crosshead are forced downwardly at the same rate under equal pressures. When the downward stroke of the crosshead has been completed, continued operation of the motor 82 will retract the cylinder 72. The pressure in the cylinders 48 being thus relieved, the spring suspensions 52 raise the crosshead and force the oil from the cylinders 48 back into the pump chambers.

Shear control

The starting point of a shearing cycle is that at which the various parts of the shear are in the positions shown in Figures 6 and 8. After a plate has been positioned for shearing, the operator will close a push-button switch, not shown, for effecting a shearing stroke. It is important, however, that the closing of the valves 87 and 88 be properly timed with the reciprocation of the cylinder 72, regardless of the instant when the push-button is pressed. The mechanism shown

in Figure 6 effects this result. A limit switch 105, mounted on a bracket secured to the gear case, is driven from the shaft 81 by a chain-and-sprocket drive 106 and bevel gearing 107. The limit switch functions in a known manner to complete an energizing circuit for a solenoid-operated mechanism adapted to close valves 87 and 88, only when the cylinder 72 is fully retracted. This mechanism operates the rock shaft 99 in the valve block 71 to shift the control valves. It includes a solenoid 108 adapted to be energized on the closing of its circuit by the limit switch. This circuit is set up in advance by manual operation of the push-button which must be continuously held down to start and carry through a shearing cycle. The solenoid actuates a bell crank 109 pivoted on the gear case at 110, acting through a collapsible spring linkage 110a. The bell crank 109 has one arm which is generally horizontal and another arm 109b which is substantially vertical. A link 111 is pivoted to the arm 109b and to a crank arm 112 secured to an end of the shaft 99 which projects outwardly of the block 71.

As stated, the starting point of a shearing cycle is that at which the various parts of the shear have the positions in which they are illustrated in Figures 6 and 8. When the parts reach such positions, in the continuous rotation of shaft 81, energization of the solenoid 108 is effected by the limit switch, which completes a circuit previously prepared by operation of the push button. The valves 87 and 88 are thus permitted to descend onto their seats. This results from counter-clockwise rotation of the bell crank 109 and the corresponding clockwise rotation of the shaft 99 effected by the link 111. The pump 70 then delivers oil under pressure to the cylinders 48 as already described and the crosshead moves downwardly.

The valves 87 and 88 are opened when the crosshead reaches the bottom of its stroke, i. e., when the pump cylinder 72 reaches the extremity of its leftward movement caused by clockwise rotation of the gear 85, even though the operator continues to hold the push button down, maintaining continued energization of solenoid 108. For this purpose, a cam 114 on the shaft 81 has a high portion which engages a roller 115 on the arm 109a of the bell crank 109, when the shaft 81 has turned through about 180 degrees. The cam thus returns the bell crank to the illustrated position, by compressing the spring linkage 110a if the solenoid continues to be energized, and raises the valves 87 and 88 from their seats. As illustrated, the cam is arranged for clockwise rotation of the shaft 81. The opening of the valves connects the reservoir 98 to the pump chambers, relieves the pressure in the cylinders 48, permitting the suspensions 52 to raise the crosshead, and insures that the pump chambers will be completely filled as the cylinder is retracted. Normally the fluid from the cylinders 48 will fill the pump chambers but any slight leakage which may occur is made up by additional fluid supplied from the reservoir. The same result follows if the operator releases the push button at any time during descent of the crosshead because this opens the solenoid circuit. On completion of a cycle, the control system is preferably locked out to prevent a repetition unless the push button has been released in which case another cycle of operations may be started when desired. The details of the electrical circuits are not shown since various arrangements may be employed, as well known in the art of automatic control.

My shear has numerous advantages over those heretofore employed. It is extremely rugged in construction and suitable for heavy duty. The mechanism is compact, simple and easily controlled. The hydraulic pump and motors are not subject to material wear or likely to get out of order. The driving motor employed need not be unduly large because substantial energy may be stored in the drive mechanism for a cutting stroke, and this energy is translated into shearing pressure with a minimum of shock.

I have illustrated and described a present preferred embodiment of the invention. It will be understood that this is by way of illustration only and that the invention may be otherwise embodied or practiced within the scope of the following claims.

I claim:

1. A plate shear comprising a pair of elongated cooperating shear blades, a first hydraulic press unit operatively connected to one of said blades, a second hydraulic press unit operatively connected to said one of said blades but at a point spaced from the first press unit, a pump for each of the units adapted to supply it with fluid under pressure, fluid connections between the pumps and the respective press units, means for substantially continuously actuating the pumps, a fluid receiver, and valve means for directing the output of the pumps to the receiver or to the respective press units.

2. A plate shear comprising a pair of elongated cooperating shear blades, a first positive-displacement hydraulic press unit operatively connected to one of said blades, a second positive-displacement hydraulic press unit operatively connected to said one of said blades but at a point spaced from the first press unit, a positive-displacement pump for each of the units adapted to supply it with fluid under pressure, fluid connections between the pumps and the respective press units, means for substantially continuously actuating the pumps, a fluid receiver, and a valve means for directing the output of the pumps to the receiver or to the respective press units.

3. A plate shear comprising a pair of elongated cooperating shear blades, a first hydraulic press unit operatively connected to one of said blades; a second hydraulic press unit operatively connected to said one of said blades but at a point spaced from the first press unit, a positive-displacement pump for each of the units adapted to supply it with fluid under pressure, fluid connections between the pumps and the respective press units, means for substantially continuously actuating the pumps, a fluid receiver, valve means for directing the output of the pumps to the receiver or to the respective press units, and means operating in timed relation with said pump for tripping said valve means.

4. A plate shear comprising a pair of elongated cooperating shear blades, a first positive-displacement hydraulic-press unit operatively connected to one of the blades, a second positive-displacement hydraulic-press unit operatively connected to one of the blades but at a point longitudinally spaced from the point of connection of the first press unit, a positive-displacement pump for each of the units, means for substantially continuously actuating the pumps, a fluid receiver, a fluid conduit connecting each pump with the receiver, a valve in each conduit whereby the pump may pump fluid to and from the receiver when the valves are open, the valves being arranged to prevent fluid flow from the pump to the receiver when closed, a constantly open fluid conduit con-

necting each pump and its corresponding press unit, each conduit bypassing the valve for its pump, means constantly biasing the shear blades against shearing movement whereby the press units, although in constant fluid communication with their respective pumps, do not effect shear movement except upon closing of the valves, and means for opening and closing the valves.

5. A plate shear comprising a pair of elongated cooperating shear blades, a first positive-displacement hydraulic-press unit operatively connected to one of the blades, a second positive-displacement hydraulic-press unit operatively connected to one of the blades but at a point longitudinally spaced from the point of connection of the first press unit, a positive-displacement pump for each of the units, means for substantially continuously actuating the pumps, a fluid receiver, a fluid conduit connecting each pump with the receiver, a valve in each conduit whereby the pump may pump fluid to and from the receiver when the valves are open, the valves being arranged to prevent fluid flow from the pump to the receiver when closed, a constantly open fluid conduit connecting each pump and its corresponding press unit, each conduit bypassing the valve for its pump, means constantly biasing the shear blades against shearing movement whereby the press units, although in constant fluid communication with their respective pumps, do not effect shear movement except upon closing of the valves.

means biasing the valves to closed position, and means for optionally holding them in open position.

6. A plate shear comprising a pair of elongated cooperating shear blades, a first positive-displacement hydraulic-press unit operatively connected to one of the blades, a second positive-displacement hydraulic-press unit operatively connected to one of the blades but at a point longitudinally spaced from the point of connection of the first press unit, a positive-displacement pump for each of the units, means for substantially continuously actuating the pumps, a fluid receiver, a fluid conduit connecting each pump with the receiver, a valve in each conduit whereby the pump may pump fluid to and from the receiver when the valves are open, the valves being arranged to prevent fluid flow from the pump to the receiver when closed, a constantly open fluid conduit connecting each pump and its corresponding press unit, each conduit bypassing the valve for its pump, means constantly biasing the shear blades against shearing movement whereby the press units, although in constant fluid communication with their respective pumps, do not effect shear movement except upon closing of the valves, means biasing the valves to closed position, means for optionally holding them in open position, and trip means operating in timed relation to the pump stroke for releasing the holding means.

LORENZ IVERSEN.
